UNITED STATES PATENT OFFICE.

ANDREW MULCAY, OF FORSYTH, GEORGIA.

DESIGN FOR A WATCH-CHARM.

SPECIFICATION forming part of Design No. 22,598, dated July 11, 1893.

Application filed January 6, 1893. Serial No. 457,550. Term of patent 3½ years.

To all whom it may concern:

Be it known that I, ANDREW MULCAY, a citizen of the United States, residing at Forsyth, in the county of Monroe and State of Georgia, have invented and produced a new and original Design for a Watch-Charm, of which the following is a specification.

Reference is to be had to the accompanying drawings forming a part of this specification, in which—

Figure 1 represents the reverse, and Fig. 2, the obverse of a medal embodying my new design.

The design comprises a star having centrally therein a circular figure, a circular band

outside of the circular figure, and rays radiating between the arms of the star. On the reverse, shown in Fig. 1, the central circular portion, or disk has thereon a representation of the globe, and the obverse has thereon a representation of the head of Christopher Columbus.

I claim—

The design for a watch charm, herein shown and described.

ANDREW MULCAY.
